UNITED STATES PATENT OFFICE.

WILLIAM R. ARNOLD, OF NEW YORK, N. Y.

APPAREL-BELT.

SPECIFICATION forming part of Letters Patent No. 683,720, dated October 1, 1901.

Application filed February 12, 1901. Serial No. 46,965. (No model.)

To all whom it may concern:

Be it known that I, WILLIAM R. ARNOLD, a citizen of the United States of America, and a resident of New York city, county and State of 5 New York, have invented certain new and useful Improvements in Apparel-Belts, of which the following is a specification.

My invention consists of an improvement in waist-belts for men's wear in which provision is made for connecting the belt and the trousers to better advantage in the matter of concealing the top of the trousers and so as to avoid the unsightly loops through which the belt is usually strung, as hereinafter described, reference being made to the accompanying drawings, in which—

Figure 1 is a perspective view of my improved belt with the ends unconnected. Fig. 2 is a diagram of the belt stretched out flat 20 and showing the inside. Fig. 3 is a front elevation of parts of the trousers and a shirt-waist or other upper garment with the belt applied as in use, part of the belt being broken out for clearer illustration of the construction. Fig. 4 is a transverse section of the belt, and Fig. 5 is a detail showing a slight modification.

The exterior portion of the belt is represented by the wide part *a*, constituting a sash 30 of ornamental character. It is preferably made in two pieces, of textile fiber or other suitable material for a sash, stitched together along both edges *b*.

c indicates a strap of about half the width 35 of part *a*, more or less attached to the inside of part *a* and preferably stitched entirely along the upper edge *d*, except its end portions *g* and *h*, to the inner ply of the part *a*. The lower edge is unattached, except at intervals, as *f*. 40 This inner strap is preferably of strong material adapted to be utilized for girding onto the body of the wearer with such tension as is required for such purpose and is provided with a buckle *i*, attached to end portion *h*, 45 with which the end portion *g* is adapted to connect. Part *g* of the strap *c* projects considerably beyond the corresponding end of part *a*, while the other end portion of part *a* projects considerably beyond the buckle to 50 overlap and conceal the buckle, said overlapping part being provided with buttonholes *j* to button onto the outside of the belt at one

side of the wearer, as indicated at *k*, Fig. 3, where it will be concealed by the coat, or it may be otherwise fastened. Strap *c* has two 55 buttonholes *l* for the hinder suspender-buttons of the trousers and two each, *m*, for the respective pairs of front suspender-buttons, which, it will be seen, may be readily buttoned onto said buttons, owing to the strap 60 *c* being unconnected at its lower edge along the buttonholes. The holes *l* are located higher in the strap than holes *m*, because the hinder buttons are generally higher, and said holes are arranged convergingly from the top 65 downward relatively to each other, so that when the belt is drawn taut for buckling in front, and thereby stretched between the buttonholes, freedom will be afforded on the 70 necks of the buttons for such stretching, and the belt will draw upward thereon, and thus maintain wider overlap of the belt above the top of the trousers, or, in other words, the belt will not tend to roll or fold on itself so much above the buttons, and thus uncover 75 the trousers at the top. Instead, however, of using the continuous strap *c* short tabs *n* may be attached to the part *a* at proper intervals, said tabs each having its buttonhole, as *l*; but in such case separate tongue and buckle 80 parts, as *g* and *h*, will have to be attached to part *a*. Such construction may be preferable when leather is principally or wholly used in the construction of the belt. The construction represented in Figs. 1, 2, 3, and 4 is that 85 which will probably be preferred when silk or other textile fabric is used; but I do not limit myself as to the material or general construction.

It will be seen that a belt so constructed 90 may be used either with or without the trousers-suspenders, being when used with them buttoned on over the suspenders, which will be first buttoned on, and in either case the buttons will not show nor the top of the trousers, and the overlap above the trousers onto 95 the upper garment will keep its place.

The belt is designed to be used with any trousers without straps. No attachment of any kind is required other than the ordinary 100 suspender-buttons for the use of such belts.

An especial advantage of the strap *c* and the tabs *n* (if used) being unattached at the lower edge is that the sash can be attached

equally well whether the buttons be on the outside of the trousers (as usually) or on the inside, (as in outing-trousers.) In the latter case the strap will be next to the body and 5 will draw over the hips in a way to be held up on the body more effectually than when the trousers intervene.

What I claim as my invention is—

1. The combination in an apparel-belt, of 10 the exterior wide part *a*, comprising a sash, inner narrow girding-strap *c* stitched along its upper edge to the part *a* beneath a wide margin of part *a*, and near its ends stitched transversely to said part *a* and provided with 15 a buckle *i* at one end, and a tongue part *g* at the other end adapted to connect with said buckle for binding the belt on the wearer, said strap *c* being unattached for the most part of its lower edge to the part *a* and having 20 holes for the trousers suspender-buttons, the tongue part *g* of strap *c* being extended beyond the corresponding end of part *a*, and part *a* having an extension beyond the buckle end of strap *c* for overlapping and concealing 25 the buckle connection of the strap *c*.
2. The combination in an apparel-belt, of

the exterior wide part *a*, comprising a sash, inner narrow girding-strap *c* stitched along its upper edge to the part *a* beneath a wide margin of part *a* and near its ends stitched 30 transversely to said part *a*, and provided with a buckle *i* at one end, and a tongue part *g* at the other end adapted to connect with said buckle for binding the belt on the wearer, said strap *c* being unattached for the most 35 part of its lower edge to the part *a* and having holes for the trousers suspender-buttons, said holes for the hinder trousers-buttons being higher in the strap than the holes for the front buttons, and converging downwardly; 40 the tongue part *g* of strap *c* being extended beyond the corresponding end of part *a*, and part *a* having an extension beyond the buckle end of strap *c* for overlapping and concealing 45 the buckle connection of the strap *c*.

Signed at New York city this 5th day of February, 1901.

WILLIAM R. ARNOLD.
